TOOL SHARPENER

James Boyd Anderson, Winchester, Ky.

Application June 14, 1934, Serial No. 730,670

4 Claims. (Cl. 51—205)

This invention relates to sharpening tools and more particularly to a tool especially designed for sharpening scissors.

The object of the invention is to provide a simple, inexpensively and thoroughly efficient device of this character by means of which a pair of scissors, shears, or other implements, which has become dull through use, may be readily sharpened by an unskilled person.

10 A further object of the invention is to provide a sharpening tool including a body portion having a holder disposed at an angle thereto and integral therewith, said holder being adapted to receive a file or strip of abrasive material so that when the device is positioned on the scissors or other implement to be sharpened, with the abrading strip or file in contact with the cutting edge of the blade and said tool reciprocated thereon, the desired angle or bevel will be imparted to said cutting edge.

15 A further object of the invention is to extend the abrading strip or block beyond the opposite ends of the holder so as to facilitate sharpening the entire length of the cutting edge of the blade, and further to form the body portion with finger-receiving seats to permit the tool to be conveniently grasped and supported when in use.

20 A still further object of the invention is generally to improve this class of devices so as to increase their utility, durability and efficiency.

25 In the accompanying drawing forming a part of this specification and in which similar numerals of reference indicate corresponding parts in all the figures of the drawing:

30 Figure 1 is a perspective view of a scissors sharpener embodying the present invention showing the manner of using the same.

Figure 2 is a perspective view of the sharpener.

Figure 3 is a transverse sectional view thereof.

35 Figure 4 is a perspective view of a modified form of the invention showing an adjustable abrasive holder.

Figure 5 is a side elevation.

Figure 6 is a top plan view.

40 The improved scissors sharpener, forming the subject-matter of the present invention, comprises a solid body portion 5 preferably substantially rectangular in shape, as shown, and formed of metal, bakelite, or other suitable material. Extending from the rear edge of the body portion and preferably integral therewith is a holder 6 having a seating channel 7 formed therein and adapted to receive a strip or block of abrasive material, indicated at 8. The holder 6 is preferably of the same width as the body portion 5

and the open side of the channel 7 faces the lower flat bearing surface 9 of the block, as best shown in Figure 3 of the drawing. The channel 7, at its junction with the body portion 5, forms a transverse shoulder 10 against which the strip of abrading material 8 rests so that the block of abrading material, when inserted within the holder, extends slightly below or beyond the bearing surface 9 of the body portion and thus prevents the cutting blade 11 of the scissors or shears from contacting with the corner of the abrasive material. The ends of the abrading strip 8 preferably project beyond the adjacent end of the holder 6, as indicated at 12, so as to permit sharpening of the extreme end of the blade, as well as the inner or pivoted end thereof. The abrading strip or block 8 is inserted within the holder from either end thereof and is retained within the holder by a clamping screw or similar fastening device 13. The rear edge of the body 5 is preferably inclined or beveled at 14, and this inclined edge and the opposite side faces of the body portion 5 are formed with seats or depressions 15 adapted to receive the fingers of the hand so as to permit the tool to be conveniently grasped and supported during the sharpening operation.

45 When sharpening a pair of scissors, said scissors are supported in the left hand and the body portion of the tool grasped between the fingers of the right hand, and positioned on the flat side of the blade 11, in the manner shown in Figure 1 of the drawing. By now reciprocating the tool over the surface of the blade, the abrading strip 8 will contact with the cutting edge and impart the desired angle or bevel thereto and thereby thoroughly sharpen the scissors. As the lower face 9 of the body portion is flat, said face forms a guide for the tool during the reciprocation thereof, and, inasmuch as the opposite ends of the abrading strip 8 project beyond the holder, the inner as well as the outer end of the blade will be sharpened, as previously stated. The inclination of the holder, with respect to the body portion 5 may be at any angle between 45° and 90° in order to take care of the different makes and grades of shears and scissors and the varying bevels on the cutting edges thereof and, when reciprocating the tool, the abrading strip will follow the original bevel of the scissors, as will be readily understood. Should the abrading strip become worn from constant use or otherwise damaged, said strip may be readily replaced by loosening the screw 13, removing the old strip and inserting a new strip within the holder. In

Figures 4 to 6, inclusive, I have illustrated a modified form of the invention in which the holder is adjustable with respect to the body portion so as to permit it to be set at any desired angle 5 or inclination relative thereto.

In this form of the invention the abrasive holder is slotted transversely to provide spaced resilient fingers 16, and the body of the tool is provided with similar fingers 17 which fit between the fingers 16 and through which passes a pivot 10 pin or bolt 18. One end of the bolt 18 is provided with a tool-receiving kerf or seat 19 while the other end thereof is threaded for engagement with a nut 20 so that, by loosening the bolt, the 15 holder may be swung laterally on its pivot to the desired position, and when the bolt is tightened the resilient fingers will be pressed together and clamp the holder in adjusted position. The bearing face of the body, at its junction 20 with the holder, is cut away to form an inclined shoulder 21 which permits swinging movement of the holder and also serves to prevent the cutting edge of the tool being sharpened from contacting with the corner of the abrading 25 strip.

It will also be understood that the device may be made in different sizes and shapes and plated or otherwise ornamented to impart an attractive appearance thereto.

While the tool is especially designed for sharpening scissors and shears, it will, of course, be understood that it may be used with equally good results for sharpening the blades of lawn mowers and other cutting implements and that, if desired, a file may be used in the holder instead 35 of an abrading strip without departing from the spirit of the invention.

Having thus described the invention, I claim:

1. A tool sharpener comprising a solid substantially rectangular body having a downwardly inclined rear face and a flat lower face, a holder 40 carried by the body extending downwardly from

the inclined rear face thereof and disposed at an angle to the flat lower face, said downwardly inclined face and the opposite sides of the body being formed with finger-receiving depressions, a sharpening element seated on the holder, and a clamping screw extending through the holder and engaging the sharpening element.

2. A tool sharpener comprising a body portion having a depending open-ended holder provided with a seating channel opening in the direction 10 of the bottom of the body portion, there being a transverse shoulder formed in the bottom of the body portion at the open side of the channel, a sharpening element insertable within the channel from either end of the holder and bearing against 15 said shoulder, and a clamping screw extending through the holder and engaging the sharpening element, the rear wall of the body portion being inclined downwardly in the direction of the holder and the opposite sides of said body portion being provided with finger-receiving recesses.

3. A tool sharpener comprising a body portion provided with spaced fingers, a holder having resilient fingers fitting between the fingers of the body portion, a bolt extending through said 25 fingers and forming a pivot, a sharpening element seated in the holder, and means engaging the bolt for clamping the fingers together to hold the holder in a set position.

4. A tool sharpener comprising a body portion 30 having finger-receiving depressions therein and provided at one edge with spaced fingers, a holder having spaced slots defining resilient fingers fitting between the fingers on the body portion, and a clamping bolt extending through the fingers 35 and forming a pivoted connection between the holder and body portion, said body portion being provided with a flat bearing face having a cut away portion defining a shoulder inclined in the direction of said pivot.

JAMES BOYD ANDERSON.
